Primary Examiner — Susan Bennett Hattan*Assistant Examiner* — Marie Fast Horse(74) *Attorney, Agent, or Firm* — Panasonic IP Management; Kerry S. Culpepper(57) **CLAIM**

We claim the ornamental design for a portable computer connection terminal with keyboard, as shown and described.

DESCRIPTION

FIG. 1 is a front perspective view of a portable computer connection terminal with keyboard of the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof shown in an alternate position for use.

The broken lines in the drawings depict portions of the portable computer connection terminal with keyboard that form no part of the claimed design. The broken lines consisting of unevenly sized dashes define the boundary of the claim, which extends to the boundary but does not include the boundary.
